(57) **CLAIM**

The ornamental design for a motorcycle tire, as shown and described.

DESCRIPTION

FIG. 1 is a perspective view of a motorcycle tire showing my new design;

FIG. 2 is a front elevation view thereof, the rear elevation view being a mirror image thereof;

FIG. 3 is a top plan view thereof; the bottom plan view being a mirror image thereof;

FIG. 4 is a right side elevation view thereof;

FIG. 5 is a left side elevation view thereof;

FIG. 6 is a fragmentary enlarged front elevation view;

FIG. 7 is a cross-sectional view taken along line 7-7 in FIG. 6; and,

FIG. 8 is a cross-sectional view taken along line 8-8 in FIG. 6.

The broken lines showing portions of the motorcycle tire are for the purpose of illustrating environmental structure and form no part of the claimed design.
